UNITED STATES PATENT OFFICE.

ERNST G. K. ANDERSON, OF CHICAGO, ILLINOIS, ASSIGNOR TO BENJAMIN ELECTRIC MANUFACTURING COMPANY, A CORPORATION OF ILLINOIS.

SWITCH-CONTAINING ELECTRIC-LAMP SOCKET.

1,238,477.

Specification of Letters Patent. Patented Aug. 28, 1917.

Application filed October 17, 1912. Serial No. 726,262.

To all whom it may concern:

Be it known that I, ERNST G. K. ANDERSON, a citizen of the United States, residing at Chicago, in the county of Cook and State of Illinois, have invented new and useful Improvements in Switch-Containing Electric-Lamp Sockets, of which the following is a full, clear, concise, and exact description, reference being had to the accompanying drawing, forming a part of this specification.

My invention pertains to switch-containing electric lamp sockets; and it is the principal object of my invention to improve upon such devices. It is a further object of my invention to improve upon the existing constructions of switches intended for use in electrical fixtures, such as lamp sockets or the like.

20 A switch-containing electric lamp socket constructed in accordance with my invention, is described in the following specification, and shown in the accompanying drawings; but it is to be understood that the invention may be embodied in other forms than that shown and described, without exceeding the scope thereof as defined in the appended claims.

In the drawings:

30 Fig. 1 is a longitudinal section through the device, with the switch in its "on" position, the section being taken on the line 1—1 of Fig. 2;

Fig. 2 is a plan of the device;

35 Fig. 3 is an inverted plan of the same;

Fig. 4 is a perspective view of the switch and switch contact;

40 Fig. 5 is a sectional view of the base, showing the manner of mounting the center contact, the section being taken on the line 5—5 of Fig. 2; and

Fig. 6 is a view showing the switch in its "off" position.

Like reference characters refer to like 45 parts throughout the following specification and the several figures of the accompanying drawings.

Referring now to the drawings, 10 indicates an insulating base in the lower end whereof, to one side of the center, is formed a chamber 11. This chamber extends a considerable distance up into the base and serves to contain the switch; it connects with the exterior of the base through a passage 12, 55 through which the switch lever extends into

a position convenient for manipulation. A threaded lamp-terminal-engaging contact 13 is attached to the lower end of the base by means of screws 14, which pass downward through the base and enter nuts within the latter. Besides the chamber 11, the base is also formed with a recess 15 (Figs. 3 and 5), in the bottom of which lies the bent-over end 16 of a metallic strip, the outer end of which is also bent over, to form the center 60 contact 17.

The center contact 17 is secured in place by means of a screw 18, which passes upward through the end 16 and through the base, and enters a binding terminal 19 at the 70 upper end of the base. The upper end of the base also carries a second binding terminal 20, which is held in place by a U-shaped contact 21, which lies in the upper end of the chamber 11, and has legs 22, which extend 75 through the upper part of the base and through the terminal 20, being bent over beyond the latter (Figs. 1, 2 and 4). The switch contained in the chamber 11, makes connection between the contact 21 and the 80 threaded contact 13 and thus completes the circuit from binding terminal to binding terminal through the lamp. The base may be formed with a side channel 40, leading to the binding terminals 19 and 20; so that 85 conductors may be conveniently led to the binding terminals when the device is used as an "angle" socket.

The sides of the chamber 11 which are 90 parallel, are formed with oppositely disposed, vertical grooves 23, for receiving the ends of a pin 24, which supports the switch-member and the actuating lever. The pin 24 is normally located by means which will 95 be described below, with its ends in the upper ends of the slots 23. Mounted on the pin 24 is a switch contact 25, being a pair of laterally separated, downwardly extending legs 26, through which the pin 24 passes. Portions of the legs 26 are bent over toward 100 each other to form abutments 28, extending across the space between the legs 26. The switch lever 29 is loosely mounted upon the pin 24, between the legs 26; and it is 105 formed with a recess 30, in which lie the abutments 28, the ends 31 and 32 of the recess 30 forming shoulders, which engage the abutments 28 when the lever is moved toward the "on" position of the switch or the 110 "off" position respectively.

A metallic plate 33 (Fig. 3) is clamped between the base 10 and the threaded contact 13, in electrical connection with the contact 13, this plate having ears 34, 5 through which the screws 14 pass. The plate 33 is formed with upwardly-jogged, outwardly-extending spring fingers 35, which press upon the lower ends of the legs 26 of the switch contact 25. These fingers 10 thus resiliently hold the contact 25, pin 24 and lever 29 in the position, in which the ends of the pin 24 engage the top ends of the lots 23.

When the switch is in the "on" position 15 (Fig. 1), the upper end of the switch contact 25 engages the contact 21, and the lower end is engaged by the spring fingers 35. If, now, the outer end of the switch lever 29 is raised, the shoulder 32, being moved into 20 engagement with the abutments 28, will force the switch contact backward, about its pivot, out of engagement with the contact 21. The ends of the legs 26 of the switch contact have beveled faces 36, thus forming corners which 25 depress the spring fingers 35 somewhat, during the rocking action described above. When their corners have passed their central position with respect to the fingers 35, the fingers cause the contact 25 to snap the 30 rest of the way, into the "off" position shown in Fig. 6. During the movements of the switch contact 25 into its "on" and "off" position, it, together with the pin 24 and the lever 29, will be depressed somewhat, owing 35 to the engagement of the front edge of the switch contact with the flat surface of the contact 21. The depression of these parts is permitted by the resiliency of the fingers 35, which, it will be remembered, support the 40 parts in question in position.

When the switch is to be moved into the "on" position, the lever 29 is depressed; so that its shoulder 31, in engagement with the abutments 28, will force the switch contact 45 forward into the position shown in Fig. 1. In order to facilitate the entrance of the upper end of the switch contact beneath the contact 21, the latter is provided with an upwardly-bent lip 37, which guides the switch 50 contact into the proper position.

The switch socket described above is simple and reliable; and its construction is such that it may be placed upon the market at a low cost, and can be assembled and taken 55 apart with ease and speed. By the provision of the two spring fingers 35, I obtain a perfect contact between the switch contact 25 and the contact 21, and avoid anything in the nature of a "line" contact.

Having thus described my invention, what 60 I claim as new and desire to secure by Letters Patent is—

1. In a switch, a fixed contact, a movable contact, means for so mounting said movable 65 contact that it may be moved about an axis,

and also moved so that the axis itself be tilted about various centers of rotation, means for moving said movable contact into and out of engagement with said fixed contact, and a plurality of spring members bearing upon said movable contact and tending 70 to move it toward said fixed contact.

2. In a switch, a fixed contact, a second fixed contact including a plurality of spring members, a movable contact engaged by said 75 second-named fixed contact for making and breaking connection between the latter and said first-named fixed contact, means for so mounting said movable contact that it may be moved about an axis, and also moved so 80 that the axis itself may be tilted about various centers of rotation, and means for moving said movable contact to effect said make and break.

3. In a switch, a pivoted member, a movable contact pivoted coaxially with said member, but independently thereof and embracing said member, said pivoted member being provided with a longitudinal slot, a member connected with said movable contact adapted to be engaged by the abutments formed at either end of said slot whereby said pivoted member and said movable contact have a lost motion connection, and a fixed contact adapted to be engaged by said 95 movable contact in one of the positions of the latter.

4. In a switch, a pivoted member, a movable contact pivoted coaxially with said member but independently thereof and embracing said member, said member and said movable contact having a lost motion connection, a fixed contact adapted to be engaged by said movable contact in one of the positions of the latter, and a pair of spring 105 members tending to move said movable contact toward said fixed contact, and engaging said movable contact one on each side of said member.

5. In a switch socket, an insulating base 110 having guideways formed therein, a fixed contact, a support member movable in said guideways, a movable contact carried by said support member, and resilient means pressing against said movable contact and thereby maintaining said support member in position in said guideways.

6. In a switch socket, an insulating base having guideways formed therein, a fixed contact, a pin having its ends located in said 120 guideways, a pivoted contact carried by said pin, a pivoted member carried by said pin for actuating said contact, and resilient means for supporting said pin, pivoted contact and actuating member in said guideways so as to permit said pivoted contact to be moved into and out of connection with said fixed contact.

7. In a switch socket, an insulating base having guideways formed therein, a fixed 130

5 contact, a pin having its ends located in said guideways, a pivoted contact carried by said pin, a pivoted member carried by said pin for actuating said contact, and a spring member engaging said pivoted contact for resiliently supporting said pivoted contact, actuating member and pin in position so as to permit said pivoted contact to be moved into and out of engagement with said fixed contact.

10 8. In a switch socket, an insulating base having a recess formed therein, said recess having guide slots formed in the sides thereof, a fixed contact disposed adjacent one end of said recess, a pin having its ends disposed in said guideways, a pivoted actuating member mounted on said pin, a contact mounted on said pin and pivoted coaxially with said actuating member but independently thereof, and a pair of resilient members engaging said pivoted contact, one on each side of said actuating member, said spring members supporting said pin, actuating member and pivoted contact in position, and tending to move said pivoted contact toward said fixed member.

15 9. In a switch socket, the combination with an insulating base, a fixed contact mounted on said base, a support, a contact mounted on said support, two spaced pin and slot bearing means for so mounting said last contact that it may be moved about an axis and also moved so that the axis itself may be tilted about various centers of rotation, a movable lever having a lost motion connection with said movable contact and adapted to move said movable contact into and out of engagement with said fixed contact, and resilient means for causing a snap action of said movable contact, said resilient means also tending to move said movable contact toward said fixed contact.

20 10. In a switch device, a pair of contacts, two spaced pin and slot bearing means for so mounting one of said contacts that it may be swung about an axis and also moved so that its axis may be tilted about various centers of rotation, means for moving one of said contacts into and out of engagement with the other, and spring means for pressing said contacts together.

25 11. In a switch device, a pair of contacts, two spaced pin and slot bearing means for so mounting one of said contacts that it may be swung about an axis and also moved so that its axis may be tilted about various centers of rotation, means for moving one of said contacts into and out of engagement with the other, and spring means for pressing said swinging contact against said other contact.

30 12. In a switch device, a pair of contacts, pivot means for one of said contacts, two spaced pin and slot bearing means for so mounting said pivot means that the pivotal

axis may be tilted about various centers of rotation and spring means for pressing one of said contacts against the other, and means for moving said pivoted contact about its pivot into and out of engagement with the other contact.

35 13. In a switch device, a pair of contacts having engaging surfaces, two spaced pin and slot bearing means for so mounting one of said contacts that it may be swung about an axis and also moved so that its axis may be tilted about various centers of rotation and spring means for pressing one of said contacts against the other, and means for moving one of said contacts into and out of engagement with the other.

40 14. A switch socket provided with two elongated spaced guideways, a supporting member having two portions pivotally and slidably mounted in said guideways so that it may be tilted about various centers of rotation, a contact carried by said supporting member, a fixed contact, and spring means for pressing said movable contact against said fixed contact.

45 15. A switch socket having a substantially cylindrical insulating base, said base having a recess therein at one side of the axis thereof, a switch arm in said recess pivoted near the lower and outer part of said recess so that its free end moves toward and from the axis of said socket, a fixed contact near the upper and outer part of said recess engaged by the free end of said arm, said recess opening out through the side of said base, and means for operating said switch arm including a lever pivoted coaxially with said arm and extending outwardly through said opening.

50 16. A receptacle comprising an insulating base, a shell contact supported thereby, a binding plate supported thereby having two apertures therein, said base having openings registering with said apertures, and a switch for controlling the circuit through said receptacle, said switch comprising a stationary contact, said contact having a pair of arms extending through said openings and apertures and secured to said binding plate.

55 17. A receptacle comprising an insulating base, a shell contact supported thereby, a binding plate supported thereby having two apertures therein, said base having openings registering with said apertures, and a switch for controlling the circuit through said receptacle, said switch comprising a stationary contact, said contact having a pair of arms extending through said openings and apertures and secured to said binding plate by bent-over portions engaging the plate.

60 18. A receptacle comprising an insulating base, a shell contact supported thereby, a switch controlling the circuit through said

receptacle comprising a fixed contact supported by said base, a contact pivoted to move substantially in a plane through the longitudinal axis of said shell, means for 5 operating said switch comprising a thumb lever extending outwardly from said receptacle and movable substantially in a plane through the longitudinal axis of said shell, and a lost motion connection between 10 said movable contact and lever, said lever

and movable contact being movable about a common axis.

In witness whereof, I have hereunto subscribed my name in the presence of two witnesses.

ERNST G. K. ANDERSON.
